UNITED STATES PATENT OFFICE.

GEORGE A. STEINER, OF SALT LAKE CITY, UTAH, ASSIGNOR TO AMERICAN LINEN
SUPPLY COMPANY, OF SALT LAKE CITY, UTAH, A CORPORATION.

TOWEL-CABINET.

1,287,784.

Specification of Letters Patent. Patented Dec. 17, 1918.

Application filed March 1, 1917. Serial No. 151,689.

To all whom it may concern:

Be it known that I, GEORGE A. STEINER, a citizen of the United States, resident of Salt Lake City, county of Salt Lake, State of Utah, have invented certain new and useful Improvements in Towel-Cabinets, of which the following is a specification.

The object of my invention is to provide a towel cabinet in which a bundle of towels may be placed and used, one at a time, without danger of the towels becoming separated from the bundle or thrown around the room where the cabinet may be placed.

A further object is to provide a means for securing towels together which will allow free use of each towel or several of them at the same time, and will also permit the use of the full wiping surface of each towel.

A further object is to avoid the use of eyelets, gromets and the like in the towels, and thereby eliminate the necessity of stringing them at the laundry and the danger of wearing or otherwise damaging the towel when the gromet is run through the laundry machinery.

Other objects of the invention will appear from the following detailed description.

The invention consists generally in various constructions and combinations, all as hereinafter described and particularly pointed out in the claims.

In the accompanying drawings forming part of this specification,

Figure 1 is a perspective view of a towel cabinet embodying my invention,

Fig. 2 is a perspective view of a portion of a cabinet, showing the preferred means for mounting the bundle of towels therein,

Fig. 3 illustrates the manner of clamping or securing the bundle of towels together,

Fig. 4 is a view of one corner of the towel, showing the tape or band thereon that is passed through the clamping device,

Fig. 5 is a detail view, showing a modified means for securing the tape extensions of the towels together.

In the drawing, 2 represents a cabinet supported on the wall or by suitable means, such as a table 3. This cabinet has a horizontal shelf 4 upon which the bundle or package of towels laid horizontally, one upon the other, is placed. Beneath this shelf is a receptacle 5 into which the soiled towels are dropped after being used. The shelf 4 is preferably provided with a recess 6 near one end and each towel 7 has a tape or band 8 stitched or otherwise secured thereto, preferably at the corner of the towel. This tape is of sufficient length to hang down over the edge of the shelf in the recess 6, and when the bundle of towels is placed on the shelf, these tapes being all at the corresponding corners of the towels, will depend in a bunch through the recess in the shelf, having been previously clamped together at the laundry by a suitable means, a form of which I have illustrated and will describe herein.

9 is a substantially U-shaped shackle and 10 a bar, shown herein as channel shaped, though any other suitable form may be used, 70 having notches 11 at the ends to receive the ends of the shackle. The shackle ends are threaded and thumb nuts 12 are mounted thereon to bear on the ends of the bar 10, the flanged edges of which contact with the 75 tapes and grip them firmly against the U-shaped shackle 9, so that it will be impossible for a towel to become separated from the others without breaking or cutting the tape, and of course, when this is done, the 80 fact that a towel has been removed will be readily ascertained by glancing at the ends of the tapes still held in the clamp. This clamp is placed on the towels before the bundle is taken away from the laundry, and can 85 be easily mounted, as no threading attachments will be required, the tapes being grasped and thrust through the shackle and the thumb nuts tightened and thereby the 90 clamp will be firmly secured and the towels held together against accidental separation. Each towel will be sufficiently free on its 95 tape to allow several persons to use towels at the same time, as there will be sufficient length of tape between the towel and the point where the tape is clamped to allow each towel to be pulled out and to one side of the cabinet, where it can be conveniently used for wiping the hands or face. This 100 feature of the device I regard as of particular construction, as in many cabinets the free use of the towels is restricted and often it is necessary for a person to stoop to an uncomfortable position before use of the towel for wiping the face can be had. Furthermore, 105 by mounting the towels with such freedom of movement as provided, the entire surface of each towel can be used and thereby a decided advantage is gained over a towel that is fastened at one corner or is provided with 110 eyelets for stringing it on a flexible or other stringer.

The clamp device may be locked on the tapes by passing a suitable chain 12' through holes in the wings of the thumb nuts and securing the ends of the chain together by 5 suitable means, such as a padlock 12".

Any suitable means may be provided for mounting the clamp on the cabinet, but I have shown in the drawings a comparatively simple type which consists in a pin 13 having a loop 14 at one end for attachment to a chain 15 to connect it with the cabinet and to receive a screw-eye or other suitable support 16 that is preferably mounted in the underside of the shelf 6. The adjacent side 10 wall of the cabinet has another screw eye 17 mounted therein and after the pin is thrust through the clamp, it is inserted into the screw eye 17 and hung on the screw eye 16 and thereby the clamp will be supported and 15 will permit the towels to be used and thrust into the receptacle 5 for return to the laundry when the bundle of clean towels has been exhausted. At such time it is only necessary to detach a pin 13 from the clamp, 20 return the bundle of soiled towels to the laundry and substitute therefor a bundle of 25 clean ones.

In Fig. 5 I have shown the tapes provided with loops 18 through which a flexible securing means, such as a chain 19, is threaded, the ends of the chain being fastened together by the padlock shown in Fig. 2. These tapes, with the towels to which they are attached, may then be placed in the cabinet, as shown in Fig. 1, or they may be hung upon any suitable support on the wall where there is insufficient room for a cabinet or where the person for whom the towels are furnished does not care for a cabinet with 30 the towels or wishes to suspend the towels upon a hook, nail, or some other device. I do not wish, therefore, to be confined to the idea of stacking the towels on the shelf, as shown in the cabinet, as they may be arranged in other ways, the essential feature being the use of the tapes or extensions, clamped or locked together in such a way that each towel may be freely used, independently of all the other towels, and the 40 person using the towel is not confined to a certain portion thereof, but can make use of the entire area of the towel as a wiping surface.

In various ways the details of construction herein shown and described may be modified and still be within the scope of my invention.

I claim as my invention:

1. A support for a bundle of towels placed 60 one upon the other, said towels having flexible extensions of less width than the towel and bunched together when the towels are assembled, and a clamp for gripping said

extensions so bunched for holding the towels together and permitting freedom of use of 65 the entire wiping surfaces of said towels.

2. A support for a bundle of towels placed one upon the other, each towel having a flexible extension at one corner thereof, said extensions being bunched together when the 70 towels are placed on said support, and a clamp for encircling said extensions so bunched to hold the towels together and permit freedom of use of the entire wiping surface thereof. 75

3. A towel cabinet having a shelf therein whereon a bundle of clean towels is placed, one upon the other, said cabinet having a receptacle beneath said shelf for the soiled towels, each towel being provided with a 80 flexible extension which is grouped with all the other extensions when the towels are placed on said shelf, and a clamping means mounted adjacent to the edge of said shelf and encircling the group of flexible extensions 85 for securing them together, said clamping means allowing freedom of use of each towel independently of all the other towels.

4. A towel rack for supporting a bundle 90 of clean towels, each having a comparatively long tape thereon, said tapes being bunched together when the towels are assembled in a bundle, means for gripping the tapes to bind them together for transport with the clean 95 towels from the laundry to the rack and for transport with the soiled towels from the rack to the laundry, said tapes permitting freedom of use of each towel and its entire wiping surface. 100

5. A means for supporting a bundle of towels in stacked form thereon, each towel having at one corner a tape secured thereto, there being a plurality of said tapes grouped at one corner of the bundle when the towels 105 are stacked, means for clamping said tapes together, thereby allowing freedom of use of the entire wiping surface of each towel, and said clamp having means for mounting it adjacent said towel supporting means. 110

6. A towel cabinet having a soiled towel receptacle in the lower portion thereof, and a support in the upper portion whereon the bundle of towels in stacked form is placed, each towel having a tape at one end thereof 115 forming a group when a number of towels are stacked, a clamp for securing said tapes together, means for supporting said clamp adjacent to said shelf, said tapes permitting freedom of use of the towels and the deposit 120 of the same after use into the receptacle beneath said shelf.

In witness whereof, I have hereunto set my hand this 23rd day of February, 1917.

GEORGE A. STEINER.
